GOFFERING MACHINE AND HEATING APPARATUS THEREFOR

Isaac Kitroser, New York, N. Y., assignor to Keller-Dorian Colorfilm Corporation, New York, N. Y., a corporation of Delaware

Application October 9, 1931, Serial No. 567,877

9 Claims. (Cl. 18—15)

My invention relates particularly to an apparatus designed for use in goffering films, as for example Keller-Dorian films, having reticulations for use in producing motion pictures in colors by 5 the Keller-Dorian method.

In providing the reticulations in the goffering on films it has been found to be very difficult to maintain the desired temperature of the apparatus so that the film support which carries a 10 light sensitive emulsion, said support being made of acetate of cellulose or nitrate of cellulose, etc., will have the desired uniform plasticity. In feeding the film into the goffering machine, a film may have a desired temperature and moisture content but it has been found very difficult to maintain the temperature of the film during 15 the goffering operation as any slight variations in the temperature of the goffering cylinder will have a corresponding effect in changing the radii of the curvature of the reticulations, thereby producing a film lacking in uniformity. Due to the microscopic size of the 20 reticulations, any such variations in curvature will have a serious effect upon the colors obtained upon the screen by passing the light through the reticulations, which are generally of a cylindrical shape, thus making the colors which are usually red, green and blue, more or less pale as produced on the screen.

The object of my invention is to provide an apparatus by means of which the desired uniformity of result is obtained by means of a goffering cylinder which is heated in such a manner as to apply at all times a desired temperature to the film. I have found that this object can be obtained by applying the heat directly to the surface of the goffering cylinder. A further object is to provide a heating device of a novel character, which is adaptable for 35 heating surfaces generally but particularly goffering cylinders, thus applying the heat to the surface the temperature of which is to be maintained but at the same time heating the entire body of the cylinder uniformly to the same temperature. This is a great advantage over internal heating devices where the heat is applied, not at the point the temperature of which is to be maintained, but at some other place in the interior of the body which is heated. This is important 40 as it has been found in practice, in goffering films, that it is necessary to keep all doors and windows closed in the room where the goffering operation is being carried out, to avoid even the presence of drafts, as otherwise there will be 45 such a lack of uniformity in the reticulations of

the film being goffered as to produce decreased color effects in the motion pictures obtained therefrom.

While my invention is capable of being carried out in many different ways, for the purpose 5 of illustration I shall describe only certain types of my invention in the accompanying drawings, in which—

Fig. 1 is a plan view of an apparatus made in accordance with my invention;

Fig. 2 is a longitudinal section of the same taken on line 2—2;

Fig. 3 is a transverse section taken on line 3—3;

Fig. 4 is a diagrammatic view showing one form 15 of circuit breaker and the circuit arrangement used therewith; and

Fig. 5 is a diagrammatic view of another form 20 of circuit breaker showing the circuit used in connection therewith.

As shown in the drawings, I have indicated a drying box 1 having a series of rolls 2 and 3 therein over which a motion picture film 4 is designed to pass while being dried, in any suitable manner, as, for example, at a temperature of 50° to 60° C. 25

with a current of air. The motion picture film 4 may be of any desired width or size and may be constructed with a support having thereon a sensitive emulsion of the usual kind. The support may be of acetate of cellulose or nitrate of 30 cellulose or any other desired material. After passing over the rolls 2 and 3 the film 4 passes out of the drying box 1 over a flanged rubber guide roll 5 having adjacent thereto an idler rubber roll 6.

The film thence passes through an inclined closed box 7 and thence over a flanged idler roll 8 from which the film passes beneath a rubber roll 9 carried on arms 10 which are supported upon a fixed rod 11 having a coil spring 12 thereon connected to one of the arms 10 and the fixed rod 11 so as to press the roll 9 downwardly against a hard rubber roll 13. After this the film passes 35 over a flanged idler rubber roll 14. The rolls 8, 13 and 14 are mounted on uprights 15 so as to be rotatably carried therein, the roll 13 being 40 provided with a steel core 17 for this purpose.

From this point the film passes beneath a rubber roll 18 having an iron core 19. This core or axis 19 is pivotally supported in arms 20 and 21 which extend upwardly respectively from sleeves 22 and 23 tightly secured on rods 24 and 25 respectively. The sleeves 22 and 23 carry on the under-faces thereof flat plates 26 and 27 to support flattened cams 28 and 29 mounted on a shaft 30 in frames 31 and 32 secured to the table by means of screws 45 50 55

33. A handle 34 is provided for moving the cams 28 and 29 so as to elevate the roll 18 or lower it into operation position. Also, the shaft 34 is capable of moving longitudinally.
- 5 34. The rods 24 and 25, as shown in Fig. 1, are secured at their ends in frames 36 and 37 which are mounted so as to be rotatable vertically independently of each other on a shaft 38 having lock-nuts 39 and 40 for retaining them in place. This 10 shaft 38 is pivotally supported at the center thereof by means of a vertical bearing 41 which passes through the same and which is carried upon a base 42 mounted upon the supporting table. Lock-nuts 43 retain the shaft 38 in place.
- 15 35. Beneath the roll 18 there is provided a steel goffering cylinder 45 having any desired conformation on the surface thereof for producing the reticulations on a goffered film. For example, in 20 producing transverse line goffering on a film the cylinder 45 will be provided with semi-cylindrical ridges running longitudinally of the cylinder, these being generally arranged so that there are between 15 and 30 lines to the millimeter around the circumference of the cylinder 45. The cylinder 25 45 has journals 46 and 47 which are journaled in the frames 31 and 32 respectively. The cylinder is driven in any desired manner, but, for example, by means of a gear 48 on the shaft 47 which meshes with a worm 49 on the end of a 30 driving shaft 50 journaled in the frame 32 and in a bearing 51. The end of the shaft 50 has a pulley 52 for driving it from any suitable source of power.
- 35 36. The film, after passing between the rolls 18 and 45, extends over a brass roll 53 having a flanged steel shaft 54 mounted in a frame 55 and thence over a brass roll 56 having a steel core 57. From this point the film passes over a rubber roller 58 mounted on a steel core 59 also journaled in said 40 frame 55 and thence beneath a similar rubber roller 60 mounted on a steel core 61 carried in pivoted arms 62 and 63 journaled on a shaft 64 which is supported in the frame 55, a spring 65 being attached to one of the arms 62 and the frame 55 so as to normally press said roll 58 against the roller 58. The roller 58 is driven by a pulley 66 having a band 67 extending therefrom to a pulley 68 on the journal 19 of the rubber roll 18. After leaving the roller 60 the film passes 50 into the box carrying a reel of the usual type for winding up the film thereon. Said reel, not shown, is driven by means of a band 69 which extends thereto from a pulley 70 on the other end of the shaft of the roller 18.
- 55 37. In order to maintain the desired temperature while the film is being goffered, the cylinder 45 is heated in such a manner as to obtain a temperature on the roll of between 100° C. and 120° C., according to the kind and condition of the film treated, but, generally, the preferred temperature is 60 110° C., the roll 45 being preferably heated for some time before starting to pass the film over the same. It is preferred, also, to rub off the cylinder 45 every three hours with a chamois cloth and benzine as a cleaning fluid, in order to remove the dust which unavoidably accumulates thereon from the film, etc. This cleaning operation 65 momentarily results in the lowering of the temperature of the roller but in view of the kind of heating apparatus which I have provided, this momentary cooling is removed and the original temperature is restored after a passage of only three or four feet of film, whereas with other 70 types of heating means used heretofore, at least 75

twenty feet of film would be so affected at each cleaning operation.

75 The heating means made in accordance with my invention is arranged to heat the roll on the surface thereof, that is to say, at the portion of the roll where the temperature is to be maintained, instead of applying the source of heat to the interior of the roll which is located a distance within the body of metal. Accordingly, I provide a heating apparatus by means of which the whole body of the cylinder is maintained at the desired temperature based upon the heating effects of hysteresis and Foucault currents. This is accomplished by providing an electromagnet 71 having electromagnetic coils 72 and 73 on poles 74 and 75 of the two arms thereof, the poles terminating adjacent to the surface of the goffering cylinder 45. Due to the passage of the film over the goffering cylinder 45, the cylinder is maintained at the desired temperature referred to, the whole 20 body of the cylinder being heated to the same temperature. The temperature is maintained uniformly by means of a thermostatic device located at the surface of the cylinder 45 and enclosed in a housing 76 which is surrounded by heat insulating material 77, such as asbestos, etc. The thermostatic couple is comprised of a silver tube 78 mounted in a supporting frame 79 at one end of the tube, the other end being connected by an internally threaded plug 80 to a quartz rod 81. The free end of the quartz rod 81 has a button 82 surrounding the end thereof and extending outwardly beyond the frame 79 and into contact with an arm 83 supported on a pivot 84 secured to the frame 79. A strong spring 85, mounted on a bracket 86 on the frame 79, presses against the button 82 so as to make contact by means of its bevelled end 87 with a bevelled end 88 on an arm 89 pivotally carried in a bracket 90 on the said frame 79. A weak spring 91 normally presses the arm 89 against a thumb-screw 92 carried in an angle arm 93 upon the frame 79. In this position the circuit is completed between the contact 92 and the arm 89 by means of a wire 94 extending from the bracket 93 to an electromagnet 95 and thence to a coil 96 in a transformer 97, designed to supply to the circuit included in the wire 94, an alternating current of about 0.1 ampere and 6 volts. The other end of said coil is connected by a wire 98 to the bracket 90. When the thermocouple becomes overheated, that is to say, when the temperature passes beyond the desired temperature of the cylinder 45, the silver tube 78 will expand, thus permitting the spring 85 to overcome the force of the spring 91 and in this way 55 break the circuit between the thumb-screw terminal 92 and the lever arm 89. This position will continue until the temperature is lowered sufficiently to restore the contact between the thumb-screw 92 and the lever arm 89. When 60 the circuit is completed between the thumb-screw 92 and the lever arm 89 the magnet 95 holds downwardly a spring arm 99 which completes a circuit with a cup provided with a body of mercury 100 which is connected by a wire 101 to a variable resistance 102 in a lead 103 for supplying current from any suitable source of alternating current, as, for instance, 110 volts, the other lead 104 for the supply current being connected to an ammeter 105 leading to the coils 70 106 and 107 on the electromagnet 71, the return wire 106 from which is connected to the spring 99. Short circuit wires 107 and 108, connected with a hand-switch 109, are bridged across the wires 106 and 107 to throw the thermostat out of 75

operation when desired. The current for the transformer 97 is supplied by wires 110 and 111 which lead from the wires 103 and 104, respectively, to a coil 112 in the transformer 97.

5 A somewhat modified form of the heating apparatus is shown in Fig. 5. In this instance, adjacent to the surface of the cylinder 45 there is provided an electric coil resistance 113 for heating the cylinder by radiation which may be provided with alternating current or direct current of any desired voltage, as, for example, 110 volts, by means of a wire 114 leading to a variable resistance 115 and an ammeter 116 which is connected to a lead 117 from any suitable source of current. Another lead 118 from said source of current is connected by a wire 119 to a cup provided with a body of mercury 120 so as to normally make contact with a spring arm 121 connected by a wire 122 to the coil 113. Wires 123 and 124, connected to the leads 117 and 118, respectively, lead to a coil 125 of a transformer 126. The other coil 127 of said transformer is connected by a wire 128 to a body of mercury 129 in a glass tube 130 having a bulb 131 supported in a metal block 132 which rests in contact with a smooth strip of surface 133 at one end of the goffering cylinder 45. When the body of mercury 129 expands, due to the rise of the temperature above, for example, 110° C., the circuit is completed between the same and a point 134 at the lower end of a screw 135 screw-threaded in a cover 136 mounted upon the tube 130. A thumb-screw 137 on the top of the screw 135, provided for the adjustment of the position of the point 134, indicates the position of adjustment by comparison with a scale 138 attached to the cover 136. A wire 139 is connected from said cover 136 to an electromagnet 140 which cooperates with the spring arm 121 to break the circuit when the electromagnet 140 is energized, the magnet 140 being connected by a wire 141 to the coil 127. In this instance, when the temperature of the cylinder 45 exceeds the desired temperature, the magnet 140 is energized to break the circuit between the spring arm 121 and the mercury cup 120, thereby cutting off the current supplied to the heating resistance 113.

While I have described my invention above in detail I wish it to be understood that many changes may be made therein without departing from the spirit of the same.

I claim:

1. In combination, a goffering cylinder and means for applying heat from the outside of the cylinder to the superficial portion thereof.

2. In combination, a goffering cylinder and means for applying heat from the outside of the cylinder to the superficial portion thereof, comprising an electromagnetic heater located at the periphery of the cylinder.

3. In combination, a goffering cylinder and means for applying heat from the outside of the cylinder to the superficial portion thereof, comprising an electric resistance heater located at the periphery of the cylinder.

4. In combination, a goffering cylinder and means for applying heat from the outside of the cylinder to the superficial portion thereof, comprising an electromagnetic heater located at the periphery of the cylinder and a thermostatic connection between said cylinder and the heater.

5. In combination, a goffering cylinder and means for applying heat from the outside of the cylinder to the superficial portion thereof, comprising an electric resistance heater located at the periphery of the cylinder and a thermostatic connection between said cylinder and the heater.

6. In combination, a goffering cylinder and means for applying heat from the outside of the cylinder to the superficial portion thereof, comprising an electromagnetic heater located at the periphery of the cylinder and a thermostatic connection between said cylinder and the heater, located at the periphery of said cylinder, the thermostat being in the form of a silver tube and quartz rod.

7. In combination, a goffering cylinder and means for applying heat from the outside of the cylinder to the superficial portion thereof, comprising an electric resistance heater located at the periphery of the cylinder and a thermostatic connection between said cylinder and the heater, located at the periphery of said cylinder, the thermostat being in the form of a silver tube and quartz rod.

8. In combination, a metal goffering cylinder adapted to produce goffered motion picture films for obtaining pictures in natural colors, means for heating the same, and an elongated thermostatic device located at the periphery of the cylinder and parallel thereto along the whole width of the goffering on the cylinder.

9. In combination, a metal goffering cylinder, means for heating the same, and a thermostatic device in the form of a thermostatic device comprised of a silver tube and a quartz rod, located at the periphery of the cylinder and parallel thereto.

ISAAC KITROSER.
